FRANK E. ALLEN.

UNITED STATES PATENT OFFICE.

FRANK E. ALLEN, OF YONKERS, NEW YORK.

DESIGN FOR CARPETS.

Specification forming part of Design No. 10,398, dated January 15, 1878; application filed December 18, 1877.
[Term of Patent 3½ years.]

To all whom it may concern:

Be it known that I, FRANK E. ALLEN, of Yonkers, in the county of Westchester and State of New York, have invented a new and original Design for Carpets, of which the following is a specification:

The nature of my design is fully shown in the accompanying photographic illustration.

I claim—

The design for carpets, as shown in the accompanying photographic illustration.

In testimony whereof I have signed my name to this specification in the presence of two subscribing witnesses.

FRANK E. ALLEN.

Witnesses:

J. E. TERRY,
C. F. BROWN.
